UNITED STATES PATENT OFFICE

2,602,564

SPACED WALL RECEPTACLE AND COVER

Manuel S. Ziskin, University Heights, and Ralph B. Billig, Erieside, Ohio, assignors to Kromex Corporation, Cleveland, Ohio, a corporation of Ohio

Application October 6, 1948, Serial No. 53,086

1 Claim. (Cl. 220—15)

1

This invention relates, as indicated, to an ice bucket or tub.

A primary object of the invention is to provide an article of the character described, in which heat transfer from the outer metallic portions of the article to the inner metallic liner of the article is minimized or reduced as far as possible.

Another object of the invention is to provide an article of the character described, in which a band or member of plastic is utilized for the purpose of breaking up metal to metal contact or continuity between outer and inner portions of the article.

A further object of the invention is to provide an article of the character described, in which heat transfer between portions of the article is reduced to a minimum, without the use of rubber gaskets and similar devices.

A still further object of the invention is to provide an article of the character described, in which handles are formed or molded integrally with the aforesaid plastic band, thereby effecting economy in manufacture and assembly of the article, and attaining additional advantages from the standpoint of heat transfer.

Other objects and advantages of the invention will be apparent during the course of the following description.

In the accompanying drawings, forming a part of this specification, and in which like numerals are employed to designate like parts throughout the same,

Fig. 1 is a side elevational view of the ice tub or bucket;

Fig. 2 is a top plan view of the ice tub or bucket;

Fig. 3 is a fragmentary cross-sectional view, on an enlarged scale, taken on the line 3—3 of Fig. 2;

Fig. 4 is a fragmentary cross-sectional view, on an enlarged scale, taken on the line 4—4 of Fig. 1, and

Fig. 5 is a fragmentary cross-sectional view, on an enlarged scale, taken on the line 5—5 of Fig. 1.

Referring more particularly to the drawings, the ice bucket or tub will be seen to comprise an outer shell 1, formed of aluminum or the like, and of generally cylindrical form and provided with a circular base or bottom 2, and an inner shell 3, similarly formed of aluminum or the like, of generally cylindrical form, and likewise provided with a circular base or bottom 4. The upper portions of the outer and inner shells are concentric with each other, while the bases or

bottoms 2 and 4 thereof are substantially parallel with each other.

The base 4 of the inner shell has rigidly secured centrally thereof an internally-threaded stake nut 5, to which a screw 6 is secured, the screw extending through a central opening in the base 2 of the outer shell, a rubber gasket 7 being interposed between the head of the screw 6 and the lower surface of the base 2. The base 2 has a central raised portion 2a, which accommodates the head of the screw 6.

It will be noted that the inner shell 3 extends vertically to a point considerably above the upper end of the shell 1, and is provided with an outwardly extending annular flange 8.

The upper end of the shell 1 forms a ledge or sill for supporting an annular shelf or band 9, of substantial thickness and molded or formed from a plastic, preferably one having good heat-insulating properties. The shell or band 9 tapers inwardly in its upper portion, which terminates in a downwardly extending, vertically disposed, annular flange 10, which, at its lower edge terminates in an inwardly extending, horizontally disposed, annular flange 11, the radially-innermost portion of which forms a seat or support for the flange 8 of the shell 3.

The lower outer wall of the plastic shell or band 9 is recessed as at 12 to a depth equivalent to the thickness of the bottom shell 1, so that with the shell 1 seated in said recess, the outer faces of the shell 1 and plastic band 9 are substantially flush with each other, presenting a smooth, streamlined, appearance.

The shell or band 9 is preferably provided at diametrically opposite points of its outer surface with a pair of handles or finger-holds 14 and 15, which are molded integrally with the band.

The space between the outer shells 1 and 9 and the inner shell 3 is filled with fiber glass 16 or similar heat and cold insulating material of light weight.

The ice bucket or tub further includes a lid or cover which comprises an upper circular portion 17 and a lower circular portion 18, both formed of aluminum. The upper portion has a downwardly extending marginal portion 19 which is curved to conform with the curvature of the upper curved portion of the band 9, being seated or disposed in a recess 20 of the band, which is equivalent in depth to the thickness of the marginal portion 19, so that the outer faces of the cover and the band 9 are substantially flush with each other, presenting a smooth and attractive streamlined appearance.

The lower or inner portion 18 of the cover is spaced from the portion 17 of the cover and has a marginal outwardly extending annular flange 21 which terminates in a vertically-extending annular flange 22 which abuts the inner face of the flange 11 of the band 9, when the cover is in closed position, and extends upwardly into contact with the upper portion 17 of the cover. The space between the portions 17 and 18 of the lid or cover is filled with fiber glass or similar heat and cold insulating material of light weight.

The portion 17 of the cover has a central indented portion 23 above which a knob 24 of plastic, similar to the plastic of which the band 9 is formed, is mounted. The knob 24 is removably secured to the cover by means of a spacer screw 25, which extends through a central opening in the portion 18 of the cover and is in threaded engagement with the knob. A lock-nut 26, secured to the screw 25, and disposed in the indentation or recess 23, maintains the screw 25 in position.

In ice buckets or tubs of this type, in which the outer and inner shells are formed entirely of metal, there is a tendency for heat from the outside atmosphere or from the surface on which the bucket is supported to be transmitted from the outer shell to the inner shell through the joint between the lid or cover and the body of the bucket, which heat causes melting of the ice cubes in the bucket in a fairly short period of time. This is due principally to the fact that there is virtually a continuous or unbroken metal to metal contact at this joint. This tendency is counteracted, to a slight extent, by the use of rubber gaskets or the like at the joint, but these gaskets are objectionable in ice buckets or the like, since they not only impart an objectionable taste to the cubes, but also constitute a nuisance in that they are difficult to maintain in place, and must be kept in a sanitary condition.

By the use of a plastic band 9, of the general construction shown, as a part of the outer shell of the bucket or tub, a number of distinct advantages are obtained.

In the first place, the metal to metal contact at the joint is broken up by the interposition of a material which is an extremely poor conductor of heat, so that transmission of heat from the shell 1 and cover to the inner shell 3 is reduced to a minimum, thereby preserving the ice cubes against too rapid melting.

In the second place, the use of gaskets at the joint between the cover and body of the bucket is eliminated, thereby overcoming the disadvantages incident to the use of such gaskets.

In the third place, since the handles 14 and 15 are formed integrally with the band 9, the cost of manufacture and assembly is reduced to a considerable extent, fastening devices at these points are eliminated, a more sanitary condition is maintained at these points due to the ease of cleaning, and the possibility of heat transfer to the inner shell from the hands during handling or lifting of the bucket is also eliminated.

As a further advantage, the plastic ring or band serves not only to center and facilitate

placement of the cover on the bucket, but also serves as a ledge for supporting the inner shell and maintaining the latter in spaced relation to the outer shell.

It is to be understood that the form of our invention, herewith shown and described, is to be taken as a preferred example of the same, and that various changes in the shape, size and arrangement of parts may be resorted to, without departing from the spirit of our invention, or the scope of the subjoined claim.

Having thus described our invention, we claim:

In an article of the character described, an outer metallic shell, and an annular insulating plastic band of substantial thickness supported upon the upper edge of the outer shell and forming a continuation thereof with the lower outer wall of the band recessed to a depth equivalent to a thickness of the outer shell for the reception of the upper end of the outer shell in flush engagement therewith whereby the outer surface of the outer shell is flush with the outer surface of the band to form a smooth outer surface for said article, said band having an integral downwardly turned flange terminating in an annular flange extending radially inwardly to a point adjacent the upper end of the inner metallic shell, the inner shell having a radially outwardly extending flange supported on and directly engaging the annular flange of the band and a means securing said inner and outer shells together thereby holding said band on said outer shell by means of the flange on the inner shell and a metallic cover having a projecting lip resting on said plastic band with the lower edge of the cover being in spaced relation to the annular flange of said band and the flange on the inner shell thereby forming an air gap therebetween, whereby the cover is insulated from said inner and outer shells, said band having a recess in its upper edge receiving the lip on said cover and lying flush with the outer surface of the cover.
